UNITED STATES PATENT OFFICE.

HENRY BLACK, OF LEWISBURG, OHIO.

IMPROVEMENT IN RAILROAD SWITCHES.

Specification forming part of Letters Patent No. 136,126, dated February 25, 1873.

To all whom it may concern:

Be it known that I, HENRY BLACK, of Lewisburg, in the county of Preble and State of Ohio, have invented a certain Improved Automatic Railway Switch, of which the following is a specification:

Nature and Objects of the Invention.

This invention relates to means for operating railway switches from and by means of the trains. Motion is transmitted from the train to the switch-rails through vertical levers, yokes engaged thereby, and operating-rods, and minor connections. The levers are supported in vertical position by means of springs and act on the yokes by cam-surfaces engaging with anti-friction rollers. The yokes are connected adjustably to the operating-rods, and so as to allow the latter independent movement. Peculiarly-constructed jacks furnish bearings for the spring-levers and guides for the yokes. To act on the operating-levers the locomotives and cars are provided with tappet-bars, adapted to be projected on either side by suitable mechanism under control of the engineers and brakemen.

Description of the Drawing.

Figure 1 is a plan view of a portion of a railway track with a locomotive thereon and fitted with switching mechanism illustrating the invention. Fig. 2 represents a longitudinal section of the track on the line a , Fig. 1, and a side elevation of a portion of the switching mechanism. Fig. 3 represents a transverse section of the track on the line a^2 , Fig. 1, and an end view of a portion of the switching mechanism and of a freight-car. Fig. 4 is a perspective view of an operating-lever and yoke with their jack, spring, and connections.

General Description.

In carrying out this invention the locomotives L , Fig. 1, and cars C , Fig. 3, are fitted with conveniently-arranged transverse sliding bars z , adapted to be projected from either side, to act as tappets. As applied to locomotives these tappets may be operated by means of longitudinal crank-shafts y extending from the cabs, connected to the bars by links x , and actuated by means of hand-cranks. As applied to cars the tappets may be oper-

ated through rack and pinion w by vertical shafts u , arranged and terminating correspondingly with the brake-shafts b . The tracks T and switching-rails s may be constructed and laid in any approved manner. The latter are connected by bars t and slide on supporting-plates r , which latter are constructed so as to present narrow ridges to prevent the rails from freezing thereto. The switching-rails are actuated through the bars t and links n , horizontal hinged plates or bell-cranks m , rods l l^2 l^3 l^4 , and yokes k k^2 k^3 k^4 by vertical levers j j^2 j^3 j^4 . Jacks or stands J furnish pivotal bearings for the operating-levers, and horizontal guides for the transmitting-yokes. Each jack is composed of a base-plate, g , and a parallel pair of arch-formed uprights, f , with horizontal guide-bars e , and a pivot, d . The operating-rods l l^2 l^3 l^4 are attached to the yokes by single nuts l' , so as to be adjustable as to length and to permit the independent movement of the rods by other yokes. The yokes are furnished with transverse anti-friction rollers k^1 to receive the impact of the levers, which act thereon by cam-extensions j^1 . The levers are preferably curved, as illustrated, and are maintained in upright position while disengaged by springs c , to which they are attached by shackles c' , and they are engaged by the tappet-bars z on the locomotives and cars to shift the switch-rails, a jack for each movement being arranged at every point from which it may be necessary to open or close a switch.

The construction of hinge-joints, couplings, and other parts not above specified, is unessential and variable with other details of mechanical construction.

The mechanism may be protected by shields of wood or other suitable material, in usual manner.

Operation.

The operation of the mechanism is illustrated in Figs. 1, 2, and 3, which represent the junction of a branch or siding, T^2 , with a single through-track, T . In the normal condition of the switch the main line is formed; and, if an up-train, for instance, is to enter the siding, as illustrated in Fig. 1, the engineer, from the cab of the locomotive L , projects the tappet-bar z , at the front end of the train, from the

right-hand side, so as to engage with the lever j , which acts through the yoke k , rod l , and connections $m n t$ to shift the switch-rails s , as required. A train leaving the siding and actuating the lever j^2 would produce the same result. Were the switch open, in order to close it from the train, illustrated in Fig. 1, the tappet z would be projected from the left-hand side, so as to engage with the lever j^3 ; or, if coming from the other end of the main track, the same position of the tappet would actuate the lever j^4 and produce the same result—namely, restore the switch to the condition in which it is illustrated. The tappets, when projected from the right side of the locomotive or car, and the levers $j j^2$ thus engaged, serve to open the switch, and the left-hand levers $j^3 j^4$ serve to close the same. In backing a train onto or out of the siding the tappet on the rear car, C, Fig. 3, would be utilized. The car-tappets would also be used in making up trains and distributing cars. Except when actuated by its adjoining yoke, or one producing the same result, each operating-rod moves independently of its yoke, and the operating-levers are immediately restored to normal position by their springs.

The peculiar curved shape of the operating-levers insures their perfect operation by tappets on locomotives and cars of different heights, the same extent of movement being imparted in all cases.

The day and night signals $S S^2$ are not claimed as parts of this present invention.

Claims.

The following is claimed as new:

1. The operating-levers $j j^2 j^3 j^4$, constructed with cam-extensions j^1 and curved, as described, to engage properly with tappet-bars z on locomotives and cars of different heights, as herein set forth.

2. The cam-levers $j j^2 j^3 j^4$ and horizontal hinged plates m , constructed as described, in combination with the yokes $k k^2 k^3 k^4$, operating-rods $l l^2 l^3 l^4$, and connections $t n$ for imparting motion to the switch-rails from tappets z on the locomotives and cars, in the manner herein specified.

3. The cam-levers $j j^2 j^3 j^4$, adapted to act on the yokes $k k^2 k^3 k^4$, in the manner described, and restored to their normal position by the spring c when released.

4. The yokes $k k^2 k^3 k^4$, connected adjustably to the operating-rods, and permitting independent movement of the latter.

5. The jacks J , constituting bearings for the spring-levers and guides for the yokes, and constructed substantially as described and shown.

HENRY BLACK.
